UNITED STATES PATENT OFFICE.

PETER LUND, OF AARHUS, DENMARK.

SAVINGS BANK.

Application filed September 2, 1924. Serial No. 735,499.

To all whom it may concern:

Be it known that PETER LUND, subject of the King of Denmark, residing at Aarhus, Denmark, has invented certain new and useful Improvements in Savings Banks, of which the following is a specification.

This invention relates to an automatic savings bank and consists in the provision of one or more transparent tubes arranged vertically on a base and adapted to receive and collect the coins into a visible pile. The device may be made up to imitate a thermometer, the base being provided with a scale in order to indicate the amount contained in the pile.

Fig. 1 of the drawing represents a front view of the device fitted with a single collecting tube,

Fig. 2, a longitudinal section of the same, and

Fig. 3, a cross-section of the coin inlet.

The device is composed of a transparent tube *a* of glass or the like, which is fitted in a groove *g* in a base *f* like a thermometer tube in its holder. The base has an eyelet *f'*, by which it can be suspended with the tube *a* in an upright position so that coins inserted in the same will be superposed and collected in a visible pile. The internal diameter of the tube is about equal to that of the coins to be collected, and there may be several tubes of equal or different diameters arranged on the same base. Each tube has on the base a scale, which indicates the amount contained in its pile of coins.

The lower end of the tube *a* is closed by a stopper *b*, whose color should be the same as that of the coins to be collected. The upper end of the tube fits in a cap *c*, which

has an upright coin slot *d*. The longitudinal edges *e* of the slot *d* are inturned, as shown in Fig. 3 to prevent the coins from being shaken out through the slot. The cap *c* is secured to the base *f*, and the tube *a* is loosely inserted therein. A clip *h* holds loosely the lower end of the tube, which is supported by a spring *j*. The lower end *k* of the spring is secured to the base *f*. There is also a safety catch *n*, which is held by a spring *m* at the back of the base and which projects through a slot *o* into engagement with the lower end of the tube *a*. To remove the tube for emptying purposes, the catch *n* is retracted and the tube depressed against the force of the spring *j*, until it is clear of the cap *c*. It can then be tilted and removed. A clip *l* is arranged so as to cover the spring *j* and the lower end of the tube *a*. The springs *j* and *m* may be made strong enough to prevent children from removing the tube.

Having now particularly described and ascertained the nature of my invention, I declare that what I claim is:

A savings bank comprising a base having an indicating scale thereon; a cap secured at one end to said base and having a slot therein for the reception of a coin; a spring secured at the other end to said base; a transparent tube supported on said spring and forced by the action of said spring into said cap to thus retain it to said base; and a spring catch secured to said base and adapted to removably lock the tube against the cap.

In testimony whereof I affix my signature.

PETER LUND.
